R. M. TAYLOR

AIR SANDING DEVICE

Filed Nov. 1, 1926

Inventor:

Roy M. Taylor;

By Robert W. Faudle,

Attorney.

UNITED STATES PATENT OFFICE.

ROY M. TAYLOR, OF RICHMOND, INDIANA.

AIR SANDING DEVICE.

Application filed November 1, 1926. Serial No. 145,469.

The object of my present invention, broadly stated, is to provide a compressed-air sanding-device for railway locomotives, or the like, the same being simple in construction, easily operated and controlled, positive in action, efficient in practice, and which can be manufactured, sold, and installed, at a comparatively low price. More specifically stated, my object is to provide a device to be connected with the sand-box, or sand-dome, of a locomotive, whereby when the said dome is provided with sand in the usual way, that the engineer who drives the locomotive carrying my device may at will cause compressed air to enter my device, whereby the sand from said dome will be positively driven into the pipes which lead therefrom to points in front of the drive wheels of the locomotive, whereby the track in front of the drive wheels will be sanded, in order to prevent the drive wheels from slipping or spinning on the track, thereby eventuating in giving the locomotive greater traction in operation, especially on heavy pulls.

My device is more particularly adapted for positively forcing the sand from the sand-dome, regardless of the condition of the sand, even though it be inadvertently wet or moistened.

Other minor objects and particular advantages of my invention will suggest themselves in the course of the following specification, and that which is new will be correlated in the claims.

The preferred means for carrying out the principles of my invention in a practical and mechanically efficient manner, is shown in the accompanying drawings, in which Figure 1 shows the outline of a locomotive, with which my invention is incorporated.

Figure 2 is a horizontal section of a portion of the sand-box, or sand-dome, of a locomotive, as taken on the line 2—2 of Fig. 1, but taken on an enlarged scale with relation thereto. Figure 3 is a top plan view of my device alone, taken on a comparatively large scale from that shown in Figs. 1 and 2. And Figure 4 is a longitudinal central section of my construction, taken on the same scale but at right-angles to that shown in Fig. 3, also showing a slight difference in the nozzle, and omitting the portion of the wall of the sand box, from that shown in Fig. 3.

Similar indices denote like parts throughout the several views.

In order that the construction, the attachment, and the several details, of my invention may be more fully understood and appreciated, I will now take up a detail description thereof, in which I will set forth the same as comprehensively as I may.

In the drawings, letter A denotes the boiler or main body of a locomotive. Letter B denotes the engineer's cab, located at the rear of said boiler. Letter C denotes one of the several drive wheels, and letter D denotes the sand-box, or sand dome, which is mounted on the top of said boiler and extends thereabove as shown.

While there are various other parts of the locomotive, some of which are shown, yet the above specifically designated parts are all that are necessary to a complete understanding of my invention.

The body, or main portion, of my device consists of a disc 1, having a threaded aperture X formed centrally therethrough. Extending back from the outer edge of the disc 1, and located on opposite sides of the aperture X are the two identical arms, 2 and 3, which carry at their rear ends the cross plate 4, which is parallel with the disc 1, and whose central portion is enlarged and also projects rearward, forming the swelled portion 5, which has a threaded aperture Z formed centrally therethrough, which aperture Z is in alinement and is concentric with the aperture X.

All of said parts, that is the disc 1, the arms 2 and 3, the plate 4, and the swell portion 5, are integral with each other, that is they form a single member, which forms the body member of the device.

Threaded into the forward end of the aperture Z is a nozzle, which may be either a long-stem nozzle 6, as shown in Figs. 2 and 3, or it may be a short nozzle 7, as shown in Fig. 4. Both the nozzle 6 and the nozzle 7, have a comparatively small central aperture therethrough, as the aperture 8 shown in Fig. 4, which extends entirely through the nozzle and is concentric with the apertures X and Z.

Threaded into the forward end of the aperture X is a comparatively large, externally threaded, nipple 9, which has a nut 10 threaded thereon. Said nipple is adapted to fit in an aperture formed through the sides

2
of the dome D, with the disc 1 contacting with the inner side of the wall of the dome D, and with the nut 10 located outside said wall. A cushioning gasket 11 also fits around the nipple 9, and it contacts with the outer face of the wall of the dome D. By turning the nut 10 on the nipple 9 it is evident that the disc 1 and the nipple 9 may be securely fastened to the dome D, as in Figs. 1, 2 and 3.

Formed entirely around and projecting centerward from near the forward end of the nipple 9 is a ridge or flange 12, shown only in Fig. 4, which is for the purpose hereinafter set forth.

Numeral 13 denotes a three-way or T-fitting, one end of which is threaded onto the forward end of the nipple 9, the forward end of said fitting being closed by the screw-plug 14, and the third portion of said fitting extends downward at an angle, with the pipe 15 threaded therein, as shown. The purpose of locating the third portion of said nipple at an angle, is to permit the pipe 15 to extend outward in order to avoid contact thereof with the boiler A.

The pipe 15 leads downward from the fitting 13 to a point directly in front of the drive-wheel C.

30 Threaded into the rear end of the member 5, that is into the aperture Z, is a comparatively small pipe 16, which extends horizontally from the member 5 to a point at the rear side of the dome D where it passes therethrough, and then extends back into the cab B to where it is provided with a valve 17, which should be within reach of the engineer in the cab.

40 A like pipe 18 extends from the valve 17 to a source of compressed air, as for instance the tank E, shown in Fig. 1.

45 It will now be understood that if my device be installed as set forth, the valve 17 being closed and with the dome D filled with sand, that the operation will be substantially as follows. When it is desired to apply sand in front of the wheel C the engineer has only to open the valve 17, which will cause a strong current of air to rush through the pipes 18 and 16, into the nozzle 6, or 7, from which nozzle the air will be directed into the body of sand, driving it forward into and through the nipple 9, into the fitting 13, and from there it will be directed downward, assisted by gravity, through the pipe 15, and delivered at the point desired.

50 It is apparent that as the air passing from said nozzle will carry with it a certain amount of sand which is the line of its travel, and as the sand is thus removed it will continue to settle down and keep the space full between the disc 1 and the plate 4.

55 And even though the sand be damp it can not become clogged up, as the pressure of air will keep it cleaned out.

The purpose of the plug 14 is two-fold: To provide means for cleaning out the interior of my device, by the removal of said plug and the insertion of a wire or the like, in the event the passage should become clogged; and secondly, the sand being driven through the nipple 9 with considerable force it will eventually wear away the metal against which the force thereof strikes, which would be the point where said plug is located. Therefore the plug acts as a baffle receiving the direct force of the sand thereagainst, and then when it becomes worn a new plug can be substituted therefor, which otherwise would require an entirely new member 13, plus the time and labor of its replacement. The flange 12 holds back the sand so it will not be jolted into the pipe 15 when the air is not turned on.

It is to be understood that the pipe 15 may have branches leading to other wheels, in addition to that shown, so that any number of drive wheels may be provided with sand simultaneously. Also it is to be understood that one of my devices may be installed on each side of the dome D, each supplying sand to the wheels on their respective sides. And also that the pipe 16 may branch inside the dome D, whereby any number of my devices connected to the dome may be all operated at one time by the operation of the valve 17.

I desire that it be understood that various changes may be made in the several details herein set forth without departing from the spirit of the invention and without sacrificing any of the advantages thereof which are new and useful.

Having now fully shown and described my invention, what I claim and desire to secure by Letters Patent of the United States, is—

1. In combination with a locomotive having a sand-dome thereon, drive-wheels, and a cab connected therewith; an air sanding device connected with the sand-dome and comprising a body member located inside the sand-dome and consisting of a disc contacting with the inner side of the wall of the sand-dome, arms extending inward from said disc, a plate connecting the inner ends of said arms with a swell portion in the center of said plate; a nozzle threaded into said swell portion and directed toward an aperture formed through said disc, a nipple extending through the wall of the dome and threaded into said aperture in the disc, a nut threaded on said nipple and adapted to be clamped upon the outer side of the dome, a T-fitting secured on the outer forward end of said nipple, a pipe leading down to a drive wheel from said fitting, a plug secured in the forward end of said fitting, an air conducting pipe leading from said nipple to the cab, a valve on the rear end of said air pipe, 120

and an air pipe leading from said valve to a source of compressed air.

2. An air sanding device for locomotives, comprising a disc, a plate spaced from the disc and integrally connected therewith, a nipple detachably connected to said disc and opening therethrough, a nozzle located in the center of said plate and directed toward the interior of said nipple, means for supplying compressed air to said nozzle to be directed from the nozzle across the space between the disc and the plate into said nipple, a flange formed around inside the nipple, a fitting secured on the outer end of said nipple, and a pipe leading from said fitting.

3. An air sanding device comprising, in

combination with a sand-dome, a disc contacting with the inside of the dome, a plate spaced inward from said disc, arms connecting the disc and the plate, a nozzle extending outward from the center of said plate and toward the center of the disc, means for supplying compressed air to pass through said nozzle, a nipple connected to said disc and extending outward through an opening in said dome, an angular fitting connected with the outer end of said nipple, there being an opening in said fitting which opening is in alinement with said nipple, and a replaceable closure for said opening.

ROY M. TAYLOR.
